UNITED STATES PATENT OFFICE.

ANDREW OVEREND, OF PHILADELPHIA, PENNSYLVANIA.

STEREOTYPE-PLATE HOLDER.

SPECIFICATION forming part of Letters Patent No. 252,694, dated January 24, 1882.

Application filed October 12, 1881. (Model.)

To all whom it may concern:

Be it known that I, ANDREW OVEREND, of Philadelphia, in the county of Philadelphia and State of Pennsylvania, have invented certain new and useful Improvements in Stereotype-Plate Holders, of which the following is a specification.

My invention consists of a metallic stereotype-block of improved construction, of improved means for holding the plates upon a stereotype-block, of a graduated gage-block for fixing or determining the margins, and of certain details of construction, all as herein-after fully described.

Reference is to be had to the accompanying drawings, forming part of this specification, in which similar letters of reference indicate corresponding parts in all the figures.

Figure 1 is a plan view of my new and improved stereotype-plate holder. Fig. 2 is a cross-section of the same, taken on the line *x*-*x* of Fig. 1. Fig. 3 is a similar section taken on the line *y*-*y* of Fig. 1. Fig. 4 is a perspective view of one of the plate clamps, and Fig. 5 is a perspective view of the gage-block.

The block A is cast of any suitable metal, and its upper surface is formed with the slots or incisions *a*, *b*, *c*, and *d*, in which the clamps B are moved to and from each other for clamping and releasing the plate E by means of the right and left hand screw-rods D D, which pass through the block from edge to edge and through the clamps, as shown in Fig. 2. The block is also formed with the incision or slot *e*, in which the gage-block C is placed, and with the slot *f* at the opposite end, in which the end clamp, F, is placed, which latter is moved to and from the plate E by the screw-rod G, and in the side of the block, near the end in which the gage-block C is placed, is formed the notch or slot *g*, in which the head of the sliding pin H rests, which pin is forced forward by the coiled spring *h* to engage with the holes *i* in the gage-block for holding the gage-block in any position for holding the plate so as to leave the desired width of margin.

Upon one end of the right and left hand screw-rods D D and of the screw-rod G are fixed the pinions *d*' *d*' and *g*', which rest in the channels *J* *J*, formed upon two sides of the block, and which are adapted to be turned by a suitable hand-rack for moving the clamps to

engage or release the plate. These pinions are formed with the fixed washers or offsets *j* upon their sides, so that when the cogs become battered from long use the ends thereof will not come in contact with the edges of the block and interfere with their revolution.

The upper surface of the block, upon which the plate E rests, is corrugated or roughened, as shown in Fig. 3 of the drawings, so that when the first impression is taken the plate will be forced down into the notches or grooves of the block, and the edges or teeth of the corrugation impressed into the metal of the plate, (which is always softer than the block,) and thus prevent the plate from slipping. The edges of the clamps are also roughened, as shown at *k* in Fig. 4, for taking firmer hold upon the beveled edges of the plate when forced against it by the screw-rods.

The power of the four screws instead of two is an advantage, in that they will fasten tighter with half the force and will open the catches with the same distance with half the strokes of the ratchet. Consequently there is only half the danger of bruising and battering the plates, and the releasing of the plate is accomplished in one-half the time, and by using spring bolt H or other device for holding the gage-block C, instead of a screw, saves the further use of the ratchet and the danger of battering the plates by the slipping of the ratchet.

Having thus fully described my invention, I claim as new and desire to secure by Letters Patent—

1. The combination, with the block A, having slots *e* *g*, and the gage-block C, having holes *i*, of the headed pin H, pressed by a coiled spring, *h*, and having a reduced end to enter one of the holes *i*, as and for the purpose specified.

2. In combination with a stereotype-block, the right and left hand screw-rods D D and the clamps B B, substantially as and for the purposes set forth.

3. The stereotype-block A, formed with the slots *a*, *b*, *c*, *d*, *e*, *f*, and *g*, in combination with the simultaneously-moving clamps B, clamp F, and gage-block C, substantially as and for the purposes set forth.

ANDREW OVEREND.
